(57) **CLAIM**

The ornamental design for a drying rack as shown and described.

DESCRIPTION

FIG. 1 is a front, left, top perspective view of a drying rack with unclaimed bag, bottles, and ring in use;

FIG. 2 is a front, left, top perspective view thereof;

FIG. 3 is a rear, right, bottom perspective view thereof;

FIG. 4 is a front elevation view thereof;

FIG. 5 is a right side elevation view thereof;

FIG. 6 is a left side elevation view thereof;

FIG. 7 is a rear elevation view thereof;

FIG. 8 is a top plan view thereof; and,

FIG. 9 is a bottom plan view thereof.

The broken lines show features of the drying rack that form no part of the claimed design.
